CLAIM

The ornamental design for a bottle, as shown and described.

DESCRIPTION

FIG. 1 is a perspective view of a bottle showing a first embodiment of our bottle design;

FIG. 2 is a front view of the bottle depicted in FIG. 1; FIG. 3 is a side view of the bottle depicted in FIG. 2 representing a partial rotation of the bottle about its vertical center axis from the front view depicted in FIG. 2; FIG. 4 is another side view of the bottle depicted in FIGS. 2 and 3 representing a partial rotation of the bottle about its vertical center axis from the front view depicted in FIG. 2 and the side view depicted in FIG. 3;

FIG. 5 is another side view of the bottle depicted in FIGS. 2, 3 and 4 representing a partial rotation of the bottle about its vertical center axis from the front view depicted in FIG. 2 and the side views depicted in FIGS. 3 and 4; FIG. 6 is a bottom plan view of the bottle depicted in FIG. 2;

FIG. 7 is a perspective view of a second embodiment of a bottle as depicted in FIG. 1;

FIG. 8 is a front view of the bottle depicted in FIG. 7; FIG. 9 is a side view of the bottle depicted in FIG. 8 representing a partial rotation of the bottle about its vertical center axis from the front view depicted in FIG. 8; FIG. 10 is another side view of the bottle depicted in FIGS. 8 and 9 representing a partial rotation of the bottle about its vertical center axis from the front view depicted in FIG. 8 and the side view depicted in FIG. 9;

FIG. 11 is another side view of the bottle depicted in FIGS. 8, 9 and 10 representing a partial rotation of the bottle about its vertical center axis from the front view depicted in FIG. 8 and the side views depicted in FIGS. 9 and 10; and, FIG. 12 is a bottom plan view of the bottle depicted in FIG. 8.

The broken lines showing the upper portion of a bottle are for illustrative purposes only and do not form part of the claimed design.
